CORDLESS ELECTRIC GRASS SHEAR

James E. Edgell, Bradford Woods, Pa., assignor to H. K. Porter Company (Delaware), Pittsburgh, Pa., a corporation of Delaware

Filed Oct. 23, 1969, Ser. No. 19,686

Term of patent 14 years

Int. Cl. D8—01

U.S. Cl. D8—8

FIG. 1

FIG. 2

FIG. 3

FIG. 4

FIG. 5

FIG. 6

FIG. 1 is a top plan view of a cordless electric grass shear embodying my new design;

FIG. 2 is a bottom view thereof;

FIG. 3 is a left side elevation view thereof;

FIG. 4 is a right side elevation view thereof;

FIG. 5 is a front elevation view thereof;

FIG. 6 is a rear elevation view thereof.

I claim:

The ornamental design for a cordless electric grass shear, substantially as shown.
